UNITED STATES PATENT OFFICE.

WILLIAM J. KENNEY AND HENRY P. GROHN, OF CHICAGO, ILLINOIS, ASSIGNEES TO
UNDERFEED STOKER COMPANY OF AMERICA, OF CHICAGO, ILLINOIS, A CORPORA-
TION OF NEW JERSEY.

CONTROLLING MECHANISM FOR STOKERS.

1,087,932.

Specification of Letters Patent. Patented Feb. 24, 1914.

Application filed June 10, 1910. Serial No. 586,139.

To all whom it may concern:

Be it known that we, WILLIAM J. KENNEY and HENRY P. GROHN, citizens of the United States, residing at Chicago, county 5 of Cook, State of Illinois, have invented a certain new and useful Improvement in Controlling Mechanism for Stokers, and declare the following to be a full, clear, and exact description of the same, such as will 10 enable others skilled in the art to which it pertains to make and use the same, reference being had to the accompanying drawings, which form a part of this specification.

15 Specifically considered, our invention relates to automatic stokers and particularly to controlling mechanism for the charging mechanism.

Viewed in this aspect, our invention has 20 for one of its objects the provision of a controlling system which will permit the charging mechanism to be controlled in a simple and convenient manner from a remote point.

25 A further object of our invention is to secure a simple and efficient controlling system which will effect the regulation of the fuel feed in such a manner as to maintain any desired relation between the fuel supply and the air supply, regardless of the 30 position of the blower or other source of air relative to the stoker.

35 A further object of our invention is to provide a stoker with local controlling means for the admission and exhaust of steam or other motive power, together with a master controlling device which may be located at a remote point.

40 A further object of our invention is to provide a stoker with valve mechanism so arranged as to make the strokes of the charging mechanism quick and positive.

45 A further object of our invention is to reduce the clearance space within the stoker cylinder and the steam inlet conduits to a minimum.

50 While our invention, specifically considered, relates to automatic stokers, there are many features general in their application and therefore, in some of its aspects, our invention is not to be considered as limited to stokers.

The various features of novelty whereby

our invention is characterized will herein-after be pointed out with particularity in 55 the claims; but for a full understanding of our invention in its various aspects, and the various objects and advantages thereof, reference is to be had to the following detailed description taken in connection with the accompanying drawings, wherein:

Figure 1 is a diagrammatic view showing a battery of four boilers equipped with stokers controlled in accordance with a preferred form of our invention; Fig. 2 is a 65 side view on an enlarged scale showing one of the stoker cylinders and the valve and valve actuating mechanism adjacent thereto, parts of the cylinder being broken away; Fig. 3 is a view looking toward the right 70 in Fig. 2, the valve casing and the cylinder containing the controlling piston being shown in section; Fig. 4 is a plan view on an enlarged scale of the selective connecting mechanism between the valve and controlling piston, the view being one looking down in Fig. 3; Fig. 5 is a side elevation of the selective mechanism, the positions of the parts being those shown in Fig. 3, and portions being broken away in order to expose 80 other portions normally hidden; Figs. 6, 7, and 8 are side views showing the three principal members of the selective mechanism in the same relative angular positions as in Fig. 5; Fig. 9 is a section taken on line 85 9-9 of Fig. 5, looking in the direction of the arrows; Fig. 10 is a view similar to Fig. 5 showing the position of the parts just before the valve is caused to begin its first downward stroke; Fig. 11 is a view 90 similar to Fig. 10 showing the condition of the parts at the completion of the downward stroke of the valve; Fig. 12 is a view similar to Figs. 10 and 11, showing the condition of the parts just as the valve reaches 95 the upper limit of its stroke; Fig. 13 is a view similar to Figs. 10 to 12 showing the condition of the parts when the valve has been returned to its intermediate position on the final downward stroke; Fig. 14 is a 100 bottom plan view of the rotatable element of the selective mechanism, showing it in the position which it occupies in Fig. 13; Fig. 15 is a side view of the regulator arm; Fig. 16 is a longitudinal section on line 105 16-16 of Fig. 17 showing a rotatable valve

which may take the place of the piston valve in the foregoing figures; Fig. 17 is a section on line 17-17 of Fig. 16; Fig. 18 is a section on line 18-18 of Fig. 17; Fig. 19 is a section on line 19-19 of Fig. 16; Fig. 20 is a side elevation of the master controlling valve shown in Fig. 1, the casing being shown in section; Fig. 21 is a section taken on line 21-21 of Fig. 20; Fig. 22 is a diagram illustrating an arrangement in which a single valve mechanism controls the admission and exhaust of steam to two stokers; Fig. 23 is a diagrammatic view showing two valves and selective connecting mechanisms associated with a single actuating device; Fig. 24 is a diagrammatic view showing an electro-magnetic control system; and Fig. 25 is a side view of one of the commutators and associated brushes forming part of the electro-magnetic controlling system.

It is necessary, in order to secure efficient results, that a definite relation shall exist between the air and the fuel supplied to furnaces; and, where there is a forced draft produced by a fan or blower, it is customary to control the fuel charging mechanism from the fan or blower so that the rate at which the fuel is fed depends upon the speed of the fan or blower. Ordinarily the blower cannot conveniently be located immediately adjacent to the charging cylinder of the stoking apparatus, and this has made it necessary to employ either a long counter shaft or similar transmission mechanism so as to bring the controlling valves near the cylinder, or else long steam conduits leading from controlling mechanism adjacent to the blower to the charging cylinder. This is particularly true where there is a battery of furnaces and a single blower for supplying air thereto. In accordance with our invention, the controlling mechanism for the charging cylinders is located adjacent to the cylinders so as to avoid the large clearance space resulting from long conduits; and a simple governing system is provided for the controller or controllers, such system including a master controller adjacent to the blower. By this arrangement cumbersome and inconvenient power transmission mechanism is avoided since the master controller may be connected with the controllers for the cylinders by a single line of piping or by a small electric cable.

In Fig. 1 of the drawings we have illustrated diagrammatically a battery of boilers with automatic stokers and a controlling system for the stoker mechanism including a fluid pressure line extending from the master controller at the blower to the local controllers at the cylinders. Referring to this figure A, A', A², and A³ represent boilers having automatic stokers indicated at B, B', B², and B³ respectively. b, b', b² and b³ repre-

sent the charging cylinders of the stokers. C represents a fan or blower driven in any suitable way as, for example, by means of an engine c; the discharge end of the blower being connected to a conduit c' which supplies air to the furnaces beneath all of the boilers. D, D', D² and D³ represent valve mechanisms adjacent to the several charging cylinders. Each valve mechanism is connected to the corresponding charging cylinder by means of short conduits d and d' which serve both as steam supply conduits and as exhaust conduits. Steam is admitted to the valve mechanisms from any suitable source as, for example, from a pipe E leading from a header E' common to all of the boilers. F is a master controller located adjacent to the blower and actuated thereby in any suitable manner. In the arrangement shown, there is a conduit f leading from the master controller to a pipe f' which is in turn connected to the several valve mechanisms by branch pipes f² to f³. The function of the master controlling valve is to produce variations in the pressure in the pipe or conduit f at regular intervals. Such variation and pressure can be effected in various ways, a simple and convenient way being to connect the pipe or conduit alternately to a source of supply of compressed fluid and to atmosphere. In the arrangement shown, the fluid medium is steam taken from the header through a pipe e, the valve serving to connect the pipe or conduit F alternately to the steam pipe e and to the exhaust port f³. It will now be seen that by our improved arrangement the clearance between each cylinder and the controlling valve therefor may be reduced to a minimum without introducing complications incident to a mechanical driving mechanism leading from the blower.

We shall now describe the controlling mechanism adjacent to each of the charging cylinders and, since these are all alike, a description of one will suffice for all. This mechanism is illustrated in Figs. 2 to 15 inclusive, and referring to these figures: G represents a valve casing containing a piston valve H. The casing has two ports g and g' communicating respectively with the pipes d and d' which lead to the opposite ends of the charging cylinder. g² is a steam supply pipe, and g³ is the exhaust. As shown most clearly in Figs. 2 and 3, the opposite ends of the valve casing are connected together by a passage g¹. The parts are so proportioned that when the valve occupies the position shown in Fig. 3, both of the ports g and g' are shut off from the steam inlet and communicate directly with the adjacent ends of the valve casing; the pipe d exhausting through the adjacent end of the casing and through the exhaust pipe g³; and the pipe d' exhausting through the

adjacent end of the casing, the port or passage g^4 and thence through the exhaust pipe. When the valve is moved downwardly, the pipe d' remains connected with the exhaust 5 and the pipe d is connected with the supply pipe g^2 . Thus steam is admitted into one end of the cylinder while the other end remains exhausted. When the valve is moved upwardly, the first operation is to cut off 10 steam from the pipe d and connect this pipe to the exhaust, a continued upward movement resulting in the closing of communication between the exhaust and pipe d' , and placing this pipe in communication with 15 the steam supply. Consequently, in the upper position of the valve, steam is admitted to the end of the cylinder which was exhausted in the other extreme position of the valve. It will be seen that each end of 20 the cylinder is exhausted before steam can enter the opposite end so that there is no back pressure at the beginning of a power stroke, and the action will be quick and positive. Furthermore, by placing the valve 25 close to the cylinder, the clearance in the cylinders and pipes is reduced to a minimum so that quicker action and greater efficiency is obtained than in the arrangement where the valve is at a considerable distance 30 from the cylinder, requiring long connections which increase the clearance. We prefer to actuate the valve by some local movable member which is controlled by the master controller and which is operatively 35 connected to the valve by some sort of adjustable selective connecting mechanism. In the arrangement shown, the movable actuating member is in the form of a piston I arranged within a cylinder I' which may 40 conveniently be formed in the one casting with the valve casing. The piston rod i^3 projects through one end of the cylinder and between it and the valve stem h is the selective connecting mechanism which will 45 be hereinafter described. The pipe f^4 communicates with the interior of the cylinder I' at the end opposite that through which the piston rod projects. It will be seen that whenever steam is admitted into the pipe f , 50 it enters the cylinder I' beneath the piston and forces the piston upwardly. The downward movement of the piston may be accomplished in any suitable way as, for example, by imposing upon it a constant pressure 55 in opposition to the pressure from below. In the arrangement shown, the upper end of the cylinder is connected to the main steam pipe E by means of a branch pipe i . The upper side of the piston, will therefore 60 be always subjected to the steam pressure of the system; but, by reason of the smaller effective area of the upper side of the piston, an upward movement of the piston will be produced whenever steam is admitted 65 upon the under side. When the pipe f is

exhausted, the steam escapes from the lower end of the cylinder and the piston is forced downwardly by reason of the steam above it. If desired, a regulating valve I^2 , illustrated as a needle valve, may be arranged 70 between the pipe f^4 and the interior of the cylinder so as to vary the rate of admission of steam beneath the piston. It will thus be seen that as the blower revolves, the master valve is driven so as alternately to admit 75 steam to and exhaust steam from the lower end of the actuating cylinder.

The selective connecting mechanism is most clearly shown in Fig. 3 and, on a larger scale, in Figs. 5 to 15. Mounted upon the 80 bracket K above the upper ends of the piston rod and valve stem, is a horizontal stud L . Upon the stud are mounted, the one in front of the other, a rotatable selective element M , a driving member N and a driven member O . These three members are shown in detail in Figs. 6 to 8, they being illustrated in the positions which they occupy in Fig. 3 where the valve is in its intermediate position. Each of the members M , N and 85 O , is loosely mounted upon the stud so as to be free to rotate thereon. The member N is connected to the upper end of the piston rod i^3 by means of a link i^2 and the member O is connected to the upper end of the valve stem 90 by means of a link h' . The member M is in the form of a ratchet wheel having a mutilated portion m and laterally projecting hub members M' and M^2 . The driving member N carries a pawl N' which is adapted to engage the ratchet teeth on the member M so as to rotate the latter step by step as the member N is oscillated. The driving member also has a wide pawl N^2 having separated noses n' and n^2 . The nose n' is adapted 95 to ride upon the hub M' which is provided at one point in its periphery with a notch m' into which the nose n' is adapted to drop in a predetermined angular position of the member M . The hub of the 100 member O is provided with a flange o extending circumferentially thereof, the flange being cut away at two points so as to form a stop or lug o' . The arm o^2 to which the link h' is attached extends radially beside 105 the lug o' near one end of the latter. The parts are so proportioned that the members o' and o^2 lie in the path of the nose n^2 of the pawl N^2 , engagement between the lug o' and the pawl being normally prevented, however, by reason of the fact that the pawl is held up as long as the pawl n' is clear of the notch or depression m' . The member 110 N carries a third pawl N^3 , this pawl being double ended and having one end, n^3 in the 115 plane of the lug o' and the other end, n^4 , in the plane of a lug m^2 on the hub M^2 . P is a spring tending normally to hold the pawl n^3 above the lug o' so as to clear the same during the movement of the parts. Q is a pawl 120

engaging with the ratchet teeth on the member M so as to prevent backward movement of this member.

The operation is as follows: Normally the valve occupies the position shown in Fig. 3 and the other parts may be assumed to be occupying the positions illustrated in this figure. As heretofore explained, the operation of the master controller causes the piston 1 to be reciprocated and this motion, it will be seen, is transformed into an oscillatory motion of the member N. When steam is admitted under the piston it causes the member N to be turned in the clockwise direction, the pawl N' engaging with the ratchet teeth on the selective element and turning the latter through a predetermined angle. When the piston moves downwardly, the pawl travels backward over the ratchet teeth and the member M remains stationary by reason of the engagement of the pawl Q with the ratchet teeth. Upon each upward movement of the piston the member M is moved forward a step, the length of which depends upon a regulating device to be hereinafter described, until the notch m' is brought beneath the nose n' of the pawl N² as indicated in Fig. 10. This permits the nose n² of the pawl to drop down in front of the lug o' on the driven member. During the next upward stroke of the piston the member M is rotated by the member n' and, when the member n² engages with the lug o', the driven member is carried along thereby until the parts assume the positions indicated in Fig. 11. The valve is now in its lowermost position so that steam is admitted to the ram end of the charging cylinder. Upon the next downward stroke of the actuating piston, the driven member remains stationary until the pawl n³ engages with the lug o' and thereafter the driven member is turned in the counter-clockwise direction until the position of the parts illustrated in Fig. 12 is reached. It will be seen that in Fig. 11 the lug m² lies in the path of the pawl n⁴ so that the latter is raised thereby upon the backward movement of the driving member, thus forcing the pawl n³ downwardly behind the lug o'. When the parts occupy the positions indicated in Fig. 12 the valve is at the upper end of its movement so that steam is being admitted to the front end of the charging cylinder and the ram forced inwardly to feed more coal into the furnace. On the next down stroke of the actuating piston the nose n² of the pawl N² rides above the lug o' (because the notch m' has passed from beneath the nose n') and engages with the arm o², causing the driven member to be rotated from the position indicated in Fig. 12 to that indicated in Fig. 13. When the piston moves downwardly the driven member and the member M remain stationary so that after the downward stroke the parts are

again in the positions indicated in Fig. 5 and the valve will thereafter remain stationary in its intermediate position until the member M has been moved around, step by step, and brought again into the position indicated in Fig. 10. It will be seen that in moving from the positions indicated in Fig. 12 to those indicated in Fig. 13, the pawl n⁴ engages with the lug m² and causes the member M to be partially rotated independently of the pawl N'. It will now be seen that the valve is positively moved into its three positions by three successive strokes of the actuating piston, while thereafter it remains in the exhaust position for an interval of time depending upon the length of the steps through which the rotary member of the selective mechanism is moved. It is therefore possible to vary the relation between the air and the coal supplied to the furnace by varying the length of the steps through which the rotary element of the selective mechanism is moved during the time the valve remains stationary; regulation being effected without altering the operation of the parts during the moving of the valve into its successive positions.

The regulating arrangement is most clearly shown in Figs. 4, 5, 9, 10 and 15. Behind the member M we have mounted upon the stud a swinging arm R having a laterally projecting flange r which is adapted to overlie the ratchet teeth on the member M. Upon the free end of the arm is a spring finger or dog S which is adapted to enter any one of a series of openings T arranged in the arc of a circle in the bracket K. In the arrangement illustrated there are nine of these openings, and the pin is shown in the middle opening. By examining Fig. 5 it will be seen that the pawl N' rides upon the flange r and does not engage with one of the ratchet teeth until the driving member has moved through a considerable angle. It will be seen that if the regulating arm is swung downwardly so as to bring the pin into one of the lower holes, the pawl will engage with the ratchet teeth at an earlier point in the movement of the driving member; while upon swinging the regulating arm upwardly, into one of the upper holes, the pawl will not engage with a ratchet tooth until a later point in the upward stroke of the driving member. By shifting the regulating arm up or down from the position indicated, the valve may be caused to be actuated less often or with greater frequency during a given number of rotations of the blower and therefore the relation between the fuel supply and the air supply may be varied to suit the conditions.

Fig. 10 makes clear another feature of the selective mechanism. It will be seen that during the upward stroke which brought the parts into the positions indicated, the pawl

N' rode for a time upon the mutilated portion *m* of the member M so that the last step through which the member M was rotated was shorter than those preceding it; the purpose of the mutilated portion being to compel the pawl to engage with the tooth immediately in advance of the mutilated portion whenever the last angle through which the rotary element is to be moved before it is brought into the position indicated in Fig. 10 is less than the angle through which it was moved in the preceding step and compelling the rotary element to be carried into a final position which brings the notch *m'* beneath the pawl *n'*.

In Figs. 20 and 21 we have illustrated a master valve which may be employed to admit the exhaust steam from the pipe *f*. This valve comprises a cylindrical casing *F'* containing a cylindrical valve *F*². The pipe *e* leads into one end of the casing so as to introduce steam into the interior of the valve. *F*² is an elongated port cut through the wall of the valve and extending a considerable distance around the same, this port being in the same transverse plane as the point at which the pipe *f* leads into the casing. When the parts are in the positions indicated in Figs. 20 and 21 steam passes through the port *F*³ and into the pipe *f*. Diametrically opposed to the port *F*³ is a second port *F*⁴ which is formed by reducing the exterior diameter of the cylindrical valve between the ends thereof for a length equal to the distance between the end of the pipe *f* and the exhaust port *f*⁶. When the valve is turned until the port *F*³ passes beyond the mouth of the pipe *f*, the port *F*⁴ comes opposite the end of this pipe and permits the pipe *f* to exhaust through the exhaust outlet *f*⁶.

Instead of using a piston valve for admitting steam to and exhausting steam from the charging cylinder, we may employ a rotary valve somewhat similar to the master valve heretofore described. Such a rotary valve may consist of a cylindrical casing *U* having ports *u* and *u'* corresponding to the ports *g* and *g'*, a steam inlet *u*² corresponding to the steam inlet *g*², and an exhaust port *u*³ corresponding to the exhaust pipe *g*³ in the other form. Within the casing is a cylindrical valve *U'* open at one end so that steam entering the casing through the port *u*² enters the interior of the valve.

*u*⁴ is a port extending through the side of the valve in position to register with either the port *u* or the port *u'* depending upon the angular position of the valve. *u*⁵ is another port formed about the exterior of the valve by reducing the exterior diameter of the valve between the ends thereof for a length equal to the distance between the ports *u* and *u*².

*U*² is a valve stem projecting through the adjacent end of the casing and adapted to

be connected to the actuating member by selective connecting mechanism similar to that heretofore described.

The valve as illustrated occupies the same position as that in Fig. 3, both ends of the charging cylinder being connected to atmosphere. When the valve is rotated 45 degrees in the clockwise direction steam is admitted into the pipe leading from port *u* while the pipe leading to port *u'* is connected to atmosphere. Upon thereafter turning the valve through an angle of 90 degrees in the counterclockwise direction, the port *u* is first connected to the exhaust port and then steam is admitted into the pipe connected with port *u'*. A movement of 45 degrees in the clockwise direction brings the valve back to the position indicated, where it remains at rest until the selective mechanism again connects it with the actuating member and causes the cycle of operations to be repeated.

Where two charging cylinders are arranged fairly close together, as indicated at *b*⁴ and *b*⁵ in Fig. 22, a single valve mechanism *D*⁴ may be employed for controlling the admission and exhaust of steam to both cylinders. In this arrangement, the pipe *d*⁰ and *d*¹⁰, corresponding to the pipes *d* and *d'* in Fig. 1, branch so as to be connected to both cylinders.

It may sometimes be desirable to have a single actuating member for a plurality of valves and this may conveniently be accomplished by introducing between each valve and the actuating member a selective mechanism similar to that heretofore described. We have shown diagrammatically such an arrangement in Fig. 23, two valves being indicated at *G*⁰, *G*⁰ and a single actuating mechanism at *I*⁰. The selective mechanism is illustrated as differing from the one just described in that a single revoluble shaft *L*⁰ takes the place of the stub shaft, the driving members *N* being fixed to this shaft, and the shaft being oscillated by the actuating member.

Instead of using fluid pressure in the controlling system for the valves and local controllers, we may employ an electro-magnetic system. Such an arrangement is illustrated in Figs. 24 and 25, wherein: an electro-magnet *V* is substituted for the actuating piston *I*, the magnet being in turn controlled from a circuit making and breaking device driven by the blower. In the arrangement shown, the magnet consists of a core *v* and two coils *v'* and *v*²; one of the coils being intended to move the core in one direction and the other in the opposite direction. Driven by the blower are two mechanically connected commutators *W* and *W'* each having two brushes, one of which is connected to a line conductor *X*. The second brush associated with the commutator *W* is connected to one

terminal of the coil v' by a wire x' . The second brush associated with the commutator W' is connected to one terminal of the coil v^2 by wires x^2 . The other terminals of the two coils are connected to line wire X' by a conductor x^3 . Each commutator is illustrated as having two bars indicated at w and w' and the commutators are so arranged that when current is flowing between the brushes of one, the brushes of the other are insulated from each other. Thus it will be seen that the magnet core is acted upon alternately by the two coils and is drawn back and forth in the same manner as the piston in the first form of our invention described. It will, of course, be understood that a particular electrical system illustrated is only diagrammatic and that the arrangement may be widely varied so long as there is an electric or electro-magnetic control system including a master controller actuated by the blower.

While we have illustrated and described with particularity only a single form of our invention we do not desire to be limited to the specific details so illustrated and described; but intend covering all constructions and arrangements which fall within the terms employed in the definitions of our invention constituting the appended claims.

We claim:

1. In an automatic stoking apparatus, a charging cylinder adapted to be connected with a furnace to be fed, a blower mechanism for supplying air to such furnace, a valve device adjacent to said cylinder for controlling the admission and exhaust of steam thereto, local actuating mechanism for said valve device including a reciprocable member, actuating means for said member, a controlling system for said actuating means including a controller arranged adjacent to said blower mechanism, and means driven by said blower mechanism and connected to said controller for actuating said controller.

2. In a stoker apparatus, a charging cylinder adapted to be connected to a furnace to be fed, a valve device arranged close to said cylinder for controlling the admission and exhaust of steam, an actuating means for said valve device located adjacent thereto, an energizing system for said actuating means extending therefrom to a remote point, a controller for said system located at said remote point, a blower mechanism located at said remote point and adapted to supply air to such furnace, and means driven by said blower mechanism and connected to said controller for actuating said controller.

3. In a stoker apparatus, a charging cylinder adapted to be connected to a furnace to be fed, a blower mechanism adapted to supply air to such furnace, a controller lo-

cated adjacent to said cylinder for governing the admission and exhaust of steam, a governing system for said controller including a master controller adjacent to the blower mechanism, and means driven by said blower mechanism and connected to said master controller for actuating said master controller.

4. In a stoker apparatus, a charging cylinder adapted to be connected to a furnace to be fed, a valve device for said cylinder located adjacent to the cylinder, a fluid pressure valve actuating means, a pipe extending from said actuating means to a remote point, a controlling valve in said pipe at said remote point, a blower mechanism for supplying air to such furnace, and means driven by said blower mechanism and connected to the latter valve for actuating that valve.

5. In a stoker apparatus, a plurality of charging cylinders adapted to be connected to furnaces to be fed, valve devices located close to said cylinders for governing the admission and exhaust of steam, local actuating means for said valve device, a blower mechanism located at a remote point and adapted to supply air to such furnaces, and a control system for said actuating means including a master controller, and means driven by said blower mechanism and connected to said master controller for actuating the master controller.

6. In a stoker apparatus: a charging cylinder adapted to be connected to a furnace to be fed; a valve device arranged to connect each end of the cylinder alternately to a supply of steam and to an exhaust port; a reciprocable member; mechanism arranged between said valve device and said member for causing said device to connect one end of the cylinder to the steam supply on one stroke of said member, to exhaust the latter end of the cylinder and connect the other end of the cylinder to the steam supply upon the return stroke of said member, and to connect the last mentioned end of the cylinder to exhaust upon the following stroke of said member; means associated with said mechanism for thereafter causing said valve device to remain inactive during a predetermined number of strokes of said member; and means located at a remote point for controlling said member.

7. In a stoker apparatus: a charging cylinder adapted to be connected to a furnace to be fed; a valve device arranged to connect each end of the cylinder alternately to a supply of steam and to an exhaust port; a reciprocable member, mechanism arranged between said valve device and said member for causing said device to connect one end of the cylinder to the steam supply on one stroke of said member, to exhaust the latter end of the cylinder and connect the other

end of the cylinder to the steam supply upon the return stroke of said member, and to connect the last mentioned end of the cylinder to exhaust upon the following 5 stroke of said member; means associated with said mechanism for thereafter causing said valve device to remain inactive during a predetermined number of strokes of said member; means located at a remote point 10 for controlling said member, and a regulator for varying the number of strokes during which said valve remains inactive.

8. In combination: a charging cylinder adapted to be connected to a furnace to be 15 fed; conduits leading to opposite ends of said cylinder; a steam supply pipe; a casing connected to said conduits and to said pipe and having an exhaust port; a three-position valve in said casing, said valve being 20 constructed and arranged to connect said supply pipe to one of said conduits in each of the extreme positions of said valve and to connect both of said conduits to the exhaust port in an intermediate position; and 25 controlling means for said valve constructed and arranged to move said valve from the intermediate position into one extreme position, then to the other extreme position, then back to the intermediate position, and then 30 cause the valve to remain stationary for a predetermined period.

9. In combination: a charging cylinder adapted to be connected to a furnace to be 35 fed; conduits leading to opposite ends of said cylinder; a steam supply pipe; a casing connected to said conduits and to said pipe and having an exhaust port; a three-position valve in said casing; said valve being 40 constructed and arranged to connect one of said conduits to said supply pipe and the other conduit to said exhaust port in each extreme position of the valve and to connect both of said conduits to said exhaust port in an intermediate position; and actuating 45 mechanism for said valve constructed and arranged to move said valve through successive cycles as follows: from the intermediate position to one extreme position; from the latter extreme position to the other 50 extreme position; then back to the intermediate position where it is held stationary for a predetermined period before being moved again into an extreme position.

10. In combination: a charging cylinder 55 adapted to be connected to a furnace to be fed; conduits leading to opposite ends of said cylinder; a steam supply pipe; a casing connected to said conduits and to said pipe and having an exhaust port; a three-position 60 valve in said casing; said valve being constructed and arranged to connect one of said conduits to said supply pipe and the other conduit to said exhaust port in each extreme position of the valve and to connect both of said conduits to said exhaust

port in an intermediate position; actuating mechanism for said valve constructed and arranged to move said valve through successive cycles as follows: from the intermediate position to one extreme position; 70 from the latter extreme position to the other extreme position; then back to the intermediate position where it is held stationary for a predetermined period before being moved again into an extreme position; and 75 a regulator for controlling the length of time during which said valve remains stationary in the intermediate position.

11. In combination: a charging cylinder adapted to be connected to a furnace to be 80 fed; a source of steam supply; a valve mechanism for alternately connecting opposite ends of the cylinder to said source of supply; said valve mechanism having an exhaust port and being constructed and arranged to connect both ends of the cylinder to said exhaust port in an intermediate position of the valve and to connect one end of the cylinder to said source of supply while maintaining the other end of the cylinder connected to the exhaust port in each extreme position of the valve; and actuating means for said valve constructed and arranged to move said valve successively from the intermediate position to an extreme position, then to the other extreme position, then back to the intermediate position, and to maintain the valve stationary for a predetermined length of time in the intermediate position. 90

12. In combination: a charging cylinder adapted to be connected to a furnace to be fed; a source of steam supply; a valve mechanism for alternately connecting opposite ends of the cylinder to said source of supply; said valve mechanism having an exhaust port and being constructed and arranged to connect both ends of the cylinder to said exhaust port in an intermediate position of the valve and to connect one end of the cylinder to said source of supply while maintaining the other end of the cylinder connected to the exhaust port in each extreme position of the valve; actuating means for said valve constructed and arranged to move said valve successively from the intermediate position to an extreme position, then to the other extreme position, then back to the intermediate position, and to maintain the valve stationary for a predetermined length of time in the intermediate position. 100

13. In combination: a charging cylinder adapted to be connected to a furnace to be fed; a source of steam supply; a valve mechanism adjacent to said cylinder for alternately connecting opposite ends of the cyl- 110

- inder to said source of supply; said valve mechanism having an exhaust port and being constructed and arranged to connect both ends of the cylinder to said exhaust port in an intermediate position of the valve and to connect one end of the cylinder to said source of supply while maintaining the other end of said cylinder connected with the exhaust port in each extreme position of the valve; actuating means for said valve constructed and arranged to move said valve successively from the intermediate position to an extreme position, then to the other extreme position, then back to the intermediate position, and to maintain the valve stationary for a predetermined length of time in the intermediate position; and a remote controlling device for said actuating means.
- 20 14. In combination: a charging cylinder adapted to be connected to a furnace to be fed; a source of steam supply; a valve mechanism adjacent to said cylinder for alternately connecting opposite ends of the cylinder to said source of supply; said valve mechanism having an exhaust port and being constructed and arranged to connect both ends of the cylinder to said exhaust port in an intermediate position of the valve and to connect one end of the cylinder to said source of supply while maintaining the other end of the cylinder connected to the exhaust port in each extreme position of the valve; and actuating means for said valve constructed and arranged to move said valve successively from the intermediate position to an extreme position, then to the other extreme position, then back to the intermediate position, and to maintain the valve stationary for a predetermined length of time in the intermediate position; a regulator for varying the length of time during which said valve remains stationary in the intermediate position; and a remote controlling device for said actuating means.
- 25 15. In an automatic stoker apparatus, a plurality of independent charging cylinders adapted to be connected to furnaces to be fed, a valve device adjacent to each of said cylinders for controlling the admission and exhaust of steam, a local actuating means for each device, independent adjusting means for each of said local actuating means, a common energizing system for said actuating means, a master controller in said energizing system, a blower mechanism for supplying air to such furnaces, and means driven by said blower mechanism and connected to said master controller for actuating the master controller.
- 30 16. In a stoker apparatus; a charging cylinder adapted to be connected to a furnace to be fed; a valve device arranged to connect each end of the cylinder alternately to a supply of steam and to an exhaust port; a reciprocable member; mechanism arranged between said valve device and said member for causing said device to connect one end of the cylinder to the steam supply on one stroke of said member, to exhaust the latter end of the cylinder and connect the other end to the steam supply upon the return stroke of said member, and to connect the last mentioned end of the cylinder to an exhaust port upon the following stroke of said member; means associated with said mechanism for thereafter causing said valve device to remain inactive during a predetermined number of strokes of said member; and means for actuating said member.
- 35 17. In a stoker apparatus; a charging cylinder adapted to be connected to a furnace to be fed; a valve device arranged to connect each end of the cylinder alternately to a supply of steam and to an exhaust port; a reciprocable member; mechanism arranged between said valve device and said member for causing said device to connect one end of the cylinder to the steam supply on one stroke of said member, to exhaust the latter end of the cylinder and connect the other end to the steam supply upon the return stroke of said member, and to connect the last mentioned end of the cylinder to an exhaust port upon the following stroke of said member; means associated with said mechanism for thereafter causing said valve device to remain inactive during a predetermined number of strokes of said member; actuating means for said member; and means located at a remote point for controlling said actuating means.
- 40 18. In a stoker apparatus; a charging cylinder adapted to be connected to a furnace to be fed; a valve device arranged to connect each end of the cylinder alternately to a supply of steam and to an exhaust port; a reciprocable member; mechanism arranged between said valve device and said member for causing said device to connect one end of the cylinder to the steam supply on one stroke of said member, to exhaust the latter end of the cylinder and connect the other end to the steam supply upon the return stroke of said member, and to connect the last mentioned end of the cylinder to an exhaust port upon the following stroke of said member; means associated with said mechanism for thereafter causing said valve device to remain inactive during a predetermined number of strokes of said member; actuating means for said member; and means located at a remote point for controlling said actuating means.
- 45 19. In an automatic stoking apparatus, a charging cylinder adapted to be connected to a furnace to be fed, a blower mechanism adapted to supply air to such furnace, a valve device adjacent to said cylinder for controlling the admission and exhaust of

steam, a fluid pressure mechanism for actuating said valve device, a pipe extending from said mechanism toward said blower mechanism, a valve in said pipe adjacent to the blower and means driven by said blower mechanism and connected to the latter valve for actuating that valve.

In testimony whereof, we sign this specification in the presence of two witnesses.

WILLIAM J. KENNEY.
